UNITED STATES PATENT OFFICE.

FRANK A. HAAS, OF NEW YORK, N. Y., ASSIGNOR TO M. J. WHITTALL ASSOCIATES, OF WORCESTER, MASSACHUSETTS.

DESIGN FOR A RUG.

Application filed July 11, 1922. Serial No. 3,033. Term of patent 7 years.

To all whom it may concern:

Be it known that I, FRANK A. HAAS, a citizen of the United States, residing in the city, county, and State of New York, have invented a new and original and ornamental Design for a Rug, of which the following is a specification, reference being had to the accompanying drawing, forming part thereof, which shows a plan view of a lower left-hand corner of a rug, showing my design.

I claim:

The ornamental design for a rug as shown.

FRANK A. HAAS.
